[57] CLAIM

The ornamental design for a tool tray, as shown and described.

DESCRIPTION

FIG. 1 is a perspective view of a tool tray showing my new design;

FIG. 2 is a top plan view thereof;

FIG. 3 is a side elevational view thereof;

FIG. 4 is a bottom plan view thereof;

FIG. 5 is an end elevational view thereof;

FIG. 6 is a cross-sectional view taken along line 6—6 of FIG. 2;

FIG. 7 is a cross-sectional view taken along line 7—7 of FIG. 2;

FIG. 8 is a perspective view of a second embodiment of the tool tray;

FIG. 9 is a top plan view thereof;

FIG. 10 is a side elevational view thereof;

FIG. 11 is a bottom plan view thereof;

FIG. 12 is an end elevational view thereof;

FIG. 13 is a cross-sectional view taken along line 13—13 of FIG. 9; and

FIG. 14 is a cross-sectional view taken along line 14—14 of FIG. 9.
